UNITED STATES PATENT OFFICE

99,003

DESIGN FOR A SHOE OR SIMILAR ARTICLE

Vincent De Liso, New York, N. Y.

Application January 2, 1936, Serial No. 60,388

Term of patent 3½ years

To all whom it may concern:

Be it known that I, Vincent De Liso, a citizen of the United States, residing in New York city, in the county of New York, in the State of New York, have invented a new, original, and ornamental Design for a Shoe or Similar Article, of which the following is a specification, reference being had to the accompanying drawing, forming part thereof.

I claim:

The ornamental design for a shoe or similar article, substantially as shown.

VINCENT DE LISO.
